BONE AUDITION APPARATUS

Henry Koch, Jamaica, N. Y., assignor to Dictograph Products Company, Inc., Jamaica, N. Y.

Application June 29, 1933, Serial No. 678,130

14 Claims. (Cl. 179—107)

This invention relates to audition apparatus or audiphones and has particular reference to apparatus for transmitting sound vibrations through bone as compared to transmission of sound through air.

It is well known that the majority of persons afflicted with partial or entire deafness can hear well when the sound vibrations are transmitted to the inner ear, and that the reason that such persons are deaf is because their hearing organs do not adequately respond to sound vibrations transmitted through the air. This condition can be remedied by transmitting the sound vibrations through the bone structure of the head to the inner ear by contact between the head and a member which vibrates in accordance with vibrations within the audible frequency range.

This principle has been utilized heretofore in apparatus for aiding the hearing of deaf persons in which a tympanum or reed, vibrating in accordance with audible sounds, is placed against the bony structure of the head, so that its vibrations are transmitted through the bone to the inner ear. These instruments are not satisfactory, largely because the vibration of the tympanum or reed is suppressed or otherwise interfered with by the contact between it and the head of the user. In other words, the tympanum or reed which reproduces the sounds is not free to vibrate in conformity to the sound transmitted to it and distortion results, which is frequently so violent that the user hears only confused noises and accordingly his hearing is not aided by the instrument. Furthermore, it is, even under the most favorable operating conditions, extremely difficult to maintain the uniform, light contact of the tympanum or reed on the head, which is essential even in imperfect bone audition.

In accordance with the present invention, a bone audition apparatus or audiphone is provided which is free of the objections of the former apparatus of that type, in that the degree of pressure with which the tympanum or reed engages the head does not materially affect the response or sensitivity of the instrument, the performance of which remains constant at all times, even under the most severe operating conditions.

The apparatus of this invention operates on an inertia principle, that is to say, the magnet upon which the voice or speech coil is preferably mounted, is carried by the reed and is massive so that it has a high relative inertia with respect to the reed, which bears a relatively fixed relation to the magnet, subject, of course, to the varia-

tions caused by the vibrations thereof in response to the fluctuations in the speech current traversing the coil. With this construction, the reed vibrates relatively to the magnet, which, in effect, remains stationary due to its inertia, so that where the apparatus is supported by the reed the latter may be placed against the head of the user with any degree of pressure without impairing the freedom of vibration of the reed.

It will be seen that the new apparatus of this invention remains sensitive and is uniform in operation during all conditions of use, may be used successfully by unskilled persons, and may be manufactured in large quantities with uniform operating results. The apparatus may also be employed without substantial change in connection with the usual sound detecting and amplifying systems common in audition apparatus.

For better understanding of the invention, reference may be had to the accompanying drawings, in which,

Figure 1 is an enlarged longitudinal section through the bone audition receiver of this invention, as seen along the line 1—1 of Figure 2;

Figure 2 is a transverse section of the receiver as seen along the line 2—2 of Figure 1;

Figures 3 and 4 illustrate two ways of holding the new receiver when it is in use; and

Figures 5, 6 and 7 are longitudinal sections through three modified forms of the receiver of this invention.

Referring to Figures 1 and 2 of these drawings, numeral 10 designates the casing of the instrument A of this invention. It is formed of substantially non-resonant material, such as hard rubber, a synthetic resin, or the like, and includes a cap plate 11 secured in position by screws 12. A pair of terminal plates 13 are inlaid flush with the inner surface of cap plate 11 and are fitted at their inner ends with terminals 14 and at their outer ends with contacts 15.

Adapted to engage each of contacts 15 is a contact spring 16 seated in a corresponding recess in casing 10 and engaging at its opposite end a plug 17 having a pin 18 projecting into a lateral passage 19 in the casing. The pins 18 are adapted to make electrical contact with the connectors 20 of cord 21 inserted in passages 19 for the purpose of connecting the terminal plates 13 to a conventional audition circuit including microphone 22, battery 23, as illustrated graphically in Figure 3, together with suitable amplifiers, rheostats, and the like, not shown.

Rigidly secured to the inner surface of cap plate 11 by means of screws 24 is a reed 25 of iron,

steel, their alloys, or other suitable magnetically permeable metal. One end 26 of the reed 25 is extended upwardly into the casing 10 at substantially right angles to the reed 25, so that the 5 reed is L-shaped. The upstanding end 26 of the reed 25 carries at its free end a massive permanent magnet 27, which is connected thereto by a plurality of screws 28, or the like. The mass of the permanent magnet 27 compared to the 10 mass of the reed 25 is such that the magnet 27 has a high relative inertia, the function of which will be described later.

Rigidly secured on the free end of the permanent magnet 27 by means of screws 29, or the 15 like, is the pole piece 30, the free end of which cooperates with the corresponding surface of reed 25 to form a narrow air gap which is preferably between two- and three-thousandths of an inch wide. Suitably secured on pole piece 30 20 is the speech coil 31, the terminals of which are connected by light filamentary conductors 32 to the terminals 14 of the terminal plates 13.

While the form of the invention illustrated in Figures 1 and 2 is preferred, several modifications 25 thereof may be used with equal facility and comprise different arrangements of the reed, permanent magnet and speech coil. For example, in Figure 5 the reed 25' is made perfectly flat, while the permanent magnet 27' is secured 30 to the end of and is arched over the reed 25' in the manner illustrated, carrying the speech coil 31' in the same way, while the electrical connections and other details are the same as those illustrated in Figure 1.

35 In the modification illustrated in Figure 6 the reed 25'' is also perfectly flat while an L-shaped permanent magnet 27'' is secured to the end thereof and carries not only the speech coil 31'' and the pole piece but also a contact block 33 of 40 insulating material to which are connected the speech coil terminals 32'' and the corresponding terminals of the speech cord 21, not shown.

In the arrangement of Figure 7 the reed 25''' is perfectly flat, while the U-shaped permanent 45 magnet 27''' carries at its center portion the speech coil 31''', other details being the same as those described in connection with Figure 1.

In order to hold the instrument just described 50 flexibly and without restraint, several forms of holders are provided, one of which is illustrated in Figure 3. This holder comprises a handle 34 having a flexible metal stem 35, the upper end of which carries the fork 36, which spans the casing 10 of the instrument and is fitted with pins 37 at the free ends of the tines thereof, these pins being pivotally inserted in corresponding recesses in the sides of the casing 10 at points preferably adjacent the air gap of the instrument, as is illustrated in Figures 1 and 3.

60 With this arrangement, the user, holding the handle 34 in his hand, places the plate 11 against the bony structure of his head, preferably on the upper jaw bone in front of the ear, on the mastoid bone behind the ear, or against some other convenient point on the bony structure of the head, preferably, however, adjacent the ear, although it is to be understood that if the vibrations received by the instrument are sufficiently amplified they may be transmitted from other 65 parts of the body, such as the shin bone, through the bone structure of the body to the inner ear.

Another form of holder is illustrated in Figure 4 and comprises a resilient metal band 38 fitted with a fork 36', on which is pivotally mounted 70 the instrument A in the manner described. The

band 38 is placed around the head of the user and firmly holds the instrument A against the head in the manner described.

In operation, the face plate 11 on which the reed 25 is rigidly mounted, is placed against the bony structure of the head of the user in the manner described. The audible sounds picked up by the microphone 22 and suitably amplified by apparatus not shown is transmitted to the speech coil 31, which accordingly varies the flux 10 traversing the path including the permanent magnet 27, the pole piece 30, the air gap and the reed 25 to set up fluctuating electromagnetic forces across the air gap, causing relative movement between the pole piece 30 and the reed 25 15 in accordance with the well known electromagnetic phenomenon. However, due to the relative inertia of the massive permanent magnet 27 and its appurtenant parts compared to the inertia of the light reed 25, the magnetic structure 20 27-30-31, in effect, remains stationary, while the light reed 25 vibrates with respect thereto about a fulcrum located substantially at the junction of the reed 25 and its extension 26. The vibration of the reed 25 is accordingly transmitted 25 through the bone which the face plate 11 engages to the inner ear and the user hears the sounds picked up by the microphone 22.

Owing to the fact that the supported reed 30 carries the magnet structure and vibrates relatively to the massive magnet structure, due to the high relative inertia of the latter, the degree of pressure with which the reed is applied to the vibration-transmitting surface, such as the head, is immaterial, the reed vibrating freely under 35 all normal-operating conditions. In other words, the relation between the reed and the magnet structure, i. e., the air gap, remains fixed subject to the vibration of the reed, so that the response of the reed is uniform and unsuppressed and 40 any bodily movement of the reed is accompanied by equal movement of the magnet structure because the latter is carried by the reed. Also, inasmuch as the casing 10 is directly attached to the reed, the entire casing vibrates with the reed 45 as a unit on the supporting means, such as the head band 38, holder 34, or the like.

In this important operating respect the apparatus of the present invention differs from the bone audition apparatus in current use in which 50 the magnet structure is supported and carries the vibrating tympanum or reed. The tympanum or reed accordingly bears a relatively fixed relation to the magnet structure only when no pressure or very light pressure is brought to bear on the tympanum or reed and, since the use of these instruments depends upon pressing the tympanum or reed to the head, usually by means of a button or the like attached thereto, the necessary fixed relation between the tympanum or 55 reed and the magnet structure, i. e., the air gap, is varied substantially in actual practice, depending upon the degree of pressure with which the instrument is applied, so that the free vibrations of the tympanum or reed are suppressed and the instrument responds so imperfectly to the audible 60 sounds which it is supposed to transmit that the audition is poor and frequently unintelligible to the user.

Furthermore, because it operates on the inertia 70 principle just described, the apparatus of this invention is uniformly sensitive for all persons and need not be as delicate as those in current use, but may be made rugged and strong so as to stand the most severe usage without break- 75

age or impairment of its sensitivity. Also, because of its structure, the instrument may be manufactured in large quantities with uniform operating results.

5 While certain preferred embodiments of the invention have been illustrated and described herein, it is to be understood that the invention is not limited thereby, but that the principles of operation thereof may be embodied in any suitable 10 instrument within the scope of the invention. For example, the new apparatus, which is essentially a telephone instrument, may be adapted to uses other than bone audition, such as for telephone purposes, simply by making appropriate changes 15 in the casing, the mounting of the instrument, and the like, although without substantial change it may be placed against the ear and the sound transmitted thereby in the manner of air audition devices.

10 I claim:

1. In a portable audiphone, the combination of a vibratory member, electromagnetic means carried by the member and adapted to respond to varying currents substantially throughout the 15 audible frequency range for vibrating said member, a casing supported by the member and housing said electromagnetic means, and means pivotally connected to the opposite sides of the casing for supporting it in operative connection with the bone structure of the user.

2. In portable bone audition apparatus, the combination of a vibratory member having a relatively flat surface, electromagnetic means supported thereby and including windings, a 20 magnetic gap and a floatingly-mounted mass vibrated relatively to the member across said gap in a direction substantially normal to the surface of the member in response to voice currents traversing said windings causing variation in the 25 magnetic flux across said gap, and resilient means pivotally connected to said member about an axis lying in a plane substantially normal to the said surface of said member and adjacent said gap for self-adjustably holding the said surface of 30 said member in operative connection with the bone structure of the user at a point substantially opposite said gap, whereby the said vibrations of the mass across the gap are transmitted reactively to the member and conducted through the connected bone structure to the inner ear of the user.

3. In portable bone audition apparatus, the combination of a vibratory member, resilient supporting means pivotally connected to opposite sides of the member for holding it in operative connection with the bone structure of the user, and electromagnetic means supported by the member including an elongated reed secured to the member, an elongated magnet connected at one end to the reed and extending in substantially parallel spaced relation to said reed, the association of the reed and magnet affording limited relative movement of the free end of the magnet, a pole piece on the free end of the magnet forming a gap with the corresponding end of the reed, said reed, magnet and pole piece providing a continuous magnetic flux path across said gap, and windings associated with said flux path and adapted when energized by voice currents to vary the flux across said gap and thus effect vibration between said reed and magnet and consequent reactive vibration of said member, whereby the vibrations thereof are conducted through the connected bone structure to the inner ear of the user.

connected bone structure to the inner ear of the user.

4. In a portable bone conduction audiphone, the combination of a vibratory member having a relatively flat contact surface, a hollow element 5 cooperating with the member to form a hollow housing, electromagnetic means within the housing having an armature portion secured to the member and a non-rigid portion extending free of the member, a bar magnet supported by at least one end on said non-rigid portion and extending in substantially parallel spaced relation to said member, a pole piece depending from said magnet toward said armature portion at a point spaced from said one end of the magnet to form 15 a narrow air gap with said armature portion, the said non-rigid portion affording limited vibration between said magnet and said armature portion at the gap in a direction substantially normal to said contact surface, windings on said pole 20 piece adapted when energized by voice currents to vary the flux across said gap and thus effect vibration between said armature portion and magnet in said direction whereby the member is correspondingly vibrated by reaction, and means 25 pivotally connected to opposite sides of said housing about an axis lying in a plane substantially normal to said contact surface and adjacent said gap for self-adjustably holding said contact surface at a point opposite said gap in operative connection with the bone structure of the user for conducting the vibrations of said member there-through to the inner ear.

5. In portable bone audition apparatus, the combination of a vibratory member having a 35 contact surface, resilient supporting means pivotally connected to opposite sides of the member about an axis substantially parallel to the contact surface of the member for self-adjustably holding it in operative connection with the bone 40 structure of the user, and electromagnetic means supported thereby including an elongated reed secured to the member, an elongated magnet connected at one end to the reed, the association of the reed and magnet affording limited relative 45 movement of the free end of the magnet, a pole piece on the free end of the magnet forming a gap with the reed, said reed, magnet and pole piece providing a continuous magnetic flux path across said gap, and windings associated with 50 said flux path and adapted when energized by voice currents to vary the flux across said gap and effect vibration between said reed and magnet and consequent reactive vibration of said member, whereby the vibrations thereof are conducted through the connected bone structure to the 55 inner ear of the user.

6. In portable bone audition apparatus, the combination of a vibratory member adapted to be operatively connected with the bone structure of 60 the user, electromagnetic means supported thereby including means secured to the member having an armature portion and a non-rigid portion, a bar magnet supported at one end on said non-rigid portion and extending in substantially parallel spaced relation to said member, a pole piece depending from said magnet toward said armature portion at a point spaced from said one end of the magnet to form a narrow magnetic gap 65 with said armature portion, the said non-rigid portion affording limited vibration between said magnet and said armature portion at the gap, windings on said pole piece adapted when energized by voice currents to vary the flux across said gap and thus effect vibration between said 70 75

armature portion and magnet, whereby the member is vibrated by reaction and transmits its vibrations through the bone structure to the inner ear of the user, and resilient supporting means 5 pivotally connected to opposite sides of the member about an axis adjacent said magnetic gap for holding said member in said operative connection with the bone structure of the user.

7. In a bone conduction audiphone, the combination of an elongated housing having a relatively flat contact surface, electrical means floatingly supported within said housing and adapted when energized by voice currents to vibrate relatively to said housing and thus vibrate the latter 10 by reaction, said means including an elongated member of substantial mass compared to the mass of said housing mounted at only one end on the housing and extending in substantially parallel spaced relation to said surface with its 15 opposite end free for said vibration relatively to said housing, and means pivotally connected to opposite sides of said housing for supporting said housing with said surface in operative connection with the bone structure of the user for conducting the vibrations thereof through said bone 20 structure to the inner ear.

8. In portable bone audition apparatus, the combination of a vibratory member adapted to be operatively connected with the bone structure 30 of the user, and electromagnetic means supported thereby including means secured to the member having an armature portion and a non-rigid portion, a bar magnet supported at only one end of said non-rigid portion and extending 35 in substantially parallel spaced relation to said member, a pole piece depending from said magnet toward said armature portion at a point spaced from said one end of the magnet to form a narrow magnetic gap with said armature portion, the said non-rigid portion affording limited 40 vibration between said magnet and said armature portion at the gap, and windings on said pole piece adapted when energized by voice currents to vary the flux across said gap and thus effect 45 vibration between said armature portion and magnet, whereby the member is vibrated by reaction and transmits its vibrations through the bone structure to the inner ear of the user.

9. In portable bone conduction apparatus, the combination of a vibratory member adapted to be operatively connected with the bone structure of the user, and electromagnetic means supported thereby including an elongated reed secured to the member, an elongated magnet connected 50 at only one end to the reed, the association of the reed and magnet affording limited relative movement of the free end of the magnet, a pole piece on the free end of the magnet forming a gap with the reed, said reed, magnet and pole 55 piece providing a continuous magnetic flux path across said gap, and windings associated with said flux path and adapted when energized by voice currents to vary the flux across said gap and thus to effect vibration between said reed and magnet 60 and consequent reactive vibration of said member, whereby the vibrations thereof are conducted through the connected bone structure to the inner ear of the user.

10. In portable bone audition apparatus, the combination of a vibratory member adapted to be operatively connected with the bone structure of the user, and electromagnetic means supported thereby including an elongated magnetically permeable element secured to the member, 70 a bar magnet mounted by one end only on one

end of the element with the free end of the magnet extending in longitudinal spaced relation to the said element, the association of the magnet and element affording a limited relative vibration of the free end of the magnet, a pole piece on the free end of the magnet forming a gap with the element, said element, magnet and pole piece providing a continuous flux across said gap, and windings associated with said flux path and adapted when energized by voice currents to vary 1 the flux across said gap and effect vibration between said element and the magnet and consequent reactive vibration of said member, whereby the vibrations thereof are conducted through the connected bone structure to the inner ear of 1 the user.

11. In portable bone audition apparatus, the combination of a vibratory member adapted to be operatively connected with the bone structure of the user, and electromagnetic means supported 2 thereby including an elongated magnetically permeable element secured to the member an elongated magnetic element secured only at one end to the first element and forming a gap between its other end and the first element, the 2 association of said elements affording a limited movement between them at the gap, and windings associated with at least one of said elements for varying the continuous flux longitudinally traversing said elements in response to energization 3 by voice currents to thereby effect relative vibration between said elements, whereby the resultant reactive vibration of the member is conducted through the connected bone structure to the inner 3 ear of the user.

12. In portable bone audition apparatus, the combination of a vibratory member adapted to be operatively connected with the bone structure of the user, and electromagnetic means supported thereby including an elongated magnetically permeable element secured by one portion thereof to the member with at least one other portion thereof extending freely from said member, an elongated magnetic element secured at one end only to the freely extending portion of 4 said first element and forming a gap between its other end and the first element, the association of said elements affording a limited movement 4 between them at the gap, and windings associated with at least one of said elements for varying the flux traversing said elements in response to 5 energization by voice currents to thereby effect relative vibration between said elements, whereby the resultant reactive vibration of the member is conducted through the connected bone 5 structure to the inner ear of the user.

13. In portable bone audition apparatus, the combination of a vibratory member adapted to be operatively connected with the bone structure of the user, and electromagnetic means supported 6 thereby including an elongated magnetically permeable element secured to the member, an elongated magnetic element mounted only at one end on the other element, with its free end forming a gap with said other element, one of said 6 elements being substantially U-shaped and the association of said elements affording a limited movement between them at the gap, and windings magnetically associated with at least one of 7 said elements for varying the flux traversing said elements in response to energization by voice currents to thereby effect relative vibration between 7 said elements, whereby the resultant reactive vibration of the member is conducted through the 71

connected bone structure to the inner ear of the user.

14. In a portable bone audition apparatus, the combination of a vibratory member adapted to be operatively connected with the bone structure of the user, and electromagnetic means supported thereby including an elongated magnetically permeable element secured to the member, an elongated magnetic element mounted only at one end on the other element with its free end forming a gap with said other element, at least one of said elements being substantially L-shaped

the association of said elements affording a limited movement between them at the gap, and windings magnetically associated with at least one of said elements for varying the flux traversing said elements in response to energization by voice currents to thereby effect relative vibration between said elements, whereby the resultant reactive vibration of the member is conducted through the connected bone structure to the inner ear of the user.

HENRY KOCH.
